UNITED STATES PATENT OFFICE.

DWIGHT L. SMITH, OF WATERBURY, CONNECTICUT, ASSIGNOR OF ONE-HALF
TO EARL A. SMITH, OF SAME PLACE.

SUSPENDER-BUCKLE.

SPECIFICATION forming part of Letters Patent No. 368,022, dated August 9, 1887.

Application filed June 13, 1887. Serial No. 241,195. (No model.)

To all whom it may concern:

Be it known that I, DWIGHT L. SMITH, of Waterbury, in the county of New Haven and State of Connecticut, have invented a new Improvement in Suspender-Buckles; and I do hereby declare the following, when taken in connection with accompanying drawings and the letters of reference marked thereon, to be a full, clear, and exact description of the same, and which said drawings constitute part of this specification, and represent, in—

Figure 1, a front view of the buckle complete; Fig. 2, a rear view of the same; Fig. 3, a vertical central section of the same; Figs. 4, 5, and 6, modifications.

This invention relates to an improvement in that class of buckles which are used for suspenders, and in which the buckle is adapted for detachably applying the braces.

20 The frame is of right-angular form, made from wire. It consists of two sides, A B, connected by two ends, C D. The side B at the center is bent downward to form a U-shaped loop, E. Longitudinally across the frame is a bar, F, preferably made from sheet metal, and attached at its ends to the respective ends of the frame, the bar F being substantially parallel with the two sides of the frame and about midway between them. Upon the lower 25 edge the bar F is provided with a series of teeth or spurs, a, more or less in number. The bar F preferably stands in the plane of the front of the frame, as seen in Fig. 3.

On the bar, near one or both ends, a stop, 30 b, is formed, preferably by a downward projection from the arm, the stop standing in substantially the plane of the rear side of the frame. To the lower bar, B, the clamp is hung. This clamp consists of a loop-like frame made from wire, and is composed of two sides, G H, connected by ends I J, H being the lower side. The said lower side, H, is hung to the bar B by a suitable clasp, K, which embraces both the side B of the frame 35 and the side H of the clamp. The upper side, G, of the clamp is parallel with the bar F, and is in a position to nearly reach the spurs a when in a closed position, as seen in Fig. 1.

On the loop is a downwardly-extending 40 hook, L, which hangs within the loop E on the frame. This hook is best made in the

same piece of wire which forms the clamp, and it is arranged so as to swing through the loop, E, as indicated in Figs. 1 and 3. The lower end of the hook is rounded, and is of 55 slightly greater length than the depth of the U-shaped loop E on the frame, and so that the rounded end of the hook will work over the inner side of the lower end of the loop E like a cam, and so that when in the fully closed 60 position, as seen in Fig. 3, the hook will have passed forward through the loop F, so as to bring the bearing between the loop and hook at a point back of the central line of the hook, thus tending to interlock the hook and loop in 65 its closed position, but from which the hook may be disengaged by simply pressing it backward, as indicated in broken lines, Fig. 3. In this backward position the buckle is in the proper condition for the introduction of the 70 strap. The strap is passed downward and forward through the frame above the bar F, thence returned below the bar F and above the loop, as seen in Fig. 3. Then the clamp is closed upon the front side of the strap and clamps 75 the strap against the points a, or the lower edge of the bar F, as the case may be. When the strap is thus clasped, the suspender-end is hung upon the hook, and the loop of the suspender-end prevents the possible return of 80 the hook through the loop F, and consequent disengagement of the strap.

This buckle is not only cheap in construction, but is most effective in use, and is light and tasteful in appearance.

85 While I prefer to make the clamp G operate against the lower edge of the bar F, it may bear against the front side of the bar F, as seen in Fig. 4. In this case it will be better to arrange the bar F in a plane with the rear 90 of the frame, as seen in Fig. 4, and construct it with projecting edges, as at d d, so that the upper bar of the clamp may stand in a position between the two edges, as seen in Fig. 4, and so that a very secure clamping is produced.

95 It will be understood that the stops b b will prevent the clamp from being forced entirely through the frame.

The upper edge of the clamp may be made 100 in the form of spurs, which will impinge upon the buckle in front of the frame, as seen in

Fig. 5. I therefore do not wish to be understood as limiting the invention to the construction of the clamp so as to engage the lower edge only of the bar F.

5 In some cases the braces are provided with a hook to engage an eye on the suspender buckle. To adapt this buckle to such brace attachment, the lever portion, which, as before described, terminates in a hook, will be constructed in loop shape, as seen in Fig. 6, to swing into the loop E, as seen in that figure, and so that the hook of the brace, engaging the inner loop of the buckle, will receive both the loop E of the frame and the loop of the 15 buckle, this loop of the lever being a well-known equivalent for the hook L. I wish to be understood by the term "hook" to include either termination of the loop.

I am aware that buckles have been made 20 consisting of a principal and auxiliary frame, the two parts hinged together, with a similar extension from the two parts to form the hook or brace engagement on one side of the frame, and therefore do not wish to be understood as 25 claiming, broadly, such a construction of buckle.

What I claim is—

1. A buckle consisting of a frame composed of two sides and two ends connecting said two 30 sides, the lower side having a downwardly-projecting loop, E, extending therefrom, and the said frame constructed with a longitudinal

bar, F, combined with a clamp hinged to the lower side of the frame, constructed with a hook, L, extending downward within said loop and adapted to work the one through the other, the upper edge of said clamp adapted to engage the strap between it and the said bar F, substantially as described.

2. A buckle the frame of which consists of 40 two sides, A B, connected by ends C D, the said side B constructed with a downwardly-projecting loop, E, and with a longitudinal bar, F, the said bar constructed with stops b, combined with a clamp hung to the side B, 45 the said clamp constructed with a hook, L, adapted to swing through the loop E of the frame, substantially as described.

3. A buckle consisting of a frame composed of two sides, A B, connected by ends C D, the 50 side B constructed with a downwardly-projecting loop, E, and with a longitudinal bar, F, extending from end to end of said frame, the said bar constructed with spurs upon its edge, combined with a clamp hinged to the side B of the frame, and constructed with a downwardly-projecting hook, L, adapted to work through said loop E, so as to engage the strap between the said clamp and the spurs on the bar F, substantially as described.

DWIGHT L. SMITH.
